CLAIM

The ornamental design for a wire grill brush, as shown and described.

DESCRIPTION

FIG. 1 is a front elevational view of a wire grill brush showing my new design, the rear elevational view being a mirror image thereof;

FIG. 2 is a side elevational view thereof, the opposite side being a mirror image thereof;

FIG. 3 is a top plan view thereof; and,

FIG. 4 is a bottom plan view thereof.

The broken lines showing opposing cleaning means and part of the handle illustrate portions of the grill brush that forms no part of the claimed design.
